UNITED STATES PATENT OFFICE.

ERNEST O. LINTON, OF INDIANA HARBOR, INDIANA, ASSIGNOR TO LINTON GASOLINE PROCESS COMPANY, OF CHICAGO, ILLINOIS, A CORPORATION OF DELAWARE.

PROCESS OF TREATING OIL.

Application filed December 8, 1920. Serial No. 429,190.

This invention relates to the treatment of heavy hydrocarbons to produce lighter hydrocarbons. The starting material may be any heavy hydrocarbon, but the process is mainly designed to treat heavy oils having an asphaltic base, the process being adapted to separate the asphaltic ingredient from the crude material, whether that material be of the asphalt base type or of the "paraffin-asphalt", "semi-asphalt" or mixed base type.

After the asphalt has been removed, the resulting distillate, which in many respects resembles an asphalt-free crude oil, such as Pennsylvania crude oil is capable of use in the same manner as such crude oil, for the manufacture of light products of the gasoline type or heavier products such as lubricating or cylinder oils.

My invention is particularly adapted for the production of gasoline or motor fuel oils, and I have described herein, the method and apparatus by which I obtain this type of product. The invention will be readily understood from the accompanying specification and drawings in which

Fig. 1 is a schematic representation of a refining plant;

Fig. 2 is a vertical section of a still;

Fig. 3 a plan view of a detail;

Fig. 4 an elevation of a preferred form of condenser; and

Fig. 5 a cross-section of Fig. 4 on the plane 5—5.

Referring to Fig. 1, 1 is a supply tank for the crude oil, such as an asphaltic base fuel oil, this tank being preferably heated by steam or otherwise to maintain its contents in a freely liquid condition. From the tank 1, the oil flows continuously through valved pipe 2 into the still A. Attached to the end of the pipe 2 is a receptacle 3, preferably conical, having a bottom 4, provided with a series of perforations 5. The receptacle 3 is thus suspended within the body of the still A, which is conveniently made in two parts, the upper part 6 having at its lower end a flange resting on and secured to a flange on the upper end of the lower part 7. A series of spaced lugs 8, are secured to the part 7, and extend into the brick-work of the furnace 9, and support the still, while permitting free flow of products of com-

bustion from gas or oil burners 10. Two burners are shown though preferably as many are used as will insure a uniform heating of the still. Openings, provided with dampers 11, are provided in the lower portion of the combustion chamber, for admitting or excluding air to facilitate quick adjustment of the temperature to the desired degree.

The furnace 9 is provided with a suitable cover 12, in close contact with the upper portion of the still, which, as well as the vapor exit-pipe is covered with a suitable heat-insulation. The insulation on the pipe 13 extends from the still A to the condenser B. 15 and 16 are pyrometer tubes, by means of which the temperatures in the interior of the still and on the bottom thereof, can be ascertained.

The condenser B consists of a cooling tank 17 to which a cooling liquid is supplied and within which is immersed a vapor cooling device consisting of an upper pipe 18 and a lower preferably inclined pipe 19, each in open communication with a chamber formed by metal webs 20, which provide a large cooling surface to quickly and completely condense the vapors. Any other suitable form of condenser may be used, but that shown is simple in construction and efficient in operation. 21 is a manometer or mercury column to indicate the pressure conditions in the system.

The vapors from pipe 13 flow directly into pipe 18, and the condensed liquids flow out through pipe 22, into a receiving tank 23.

At its lower portion, the still A is provided with an exit pipe 24, through which the asphalt is delivered into a tank 25.

The operation of the system as thus far described, is as follows:

The crude oil, such as an asphaltic base fuel oil, of the type produced in the Oklahoma, Texas and Mexican fields is delivered through the pipe 2 on to the hot bottom 4 of the receptacle 3, over which it spreads in a thin layer, the liquid and vapor being delivered through the holes 5 into the chamber of the still, the liquid portion falling on to the heated bottom portion 7 of the still A. The temperature in the inside of the still, is carefully regulated, by means of pyrometer

15 between 830° and 860° F., preferably at 850° F., the temperature of the bottom of the still being maintained between 865° to 940° F., preferably at about 900° F., but below the point at which coke is formed.

10 The temperature within the still should not be permitted to rise above 860° F., as above that point, some of the asphaltic ingredients begin to vaporize. Nor should the 10 temperature be allowed to fall substantially below 830° F., as below that point some of the high-boiling oils would not be vaporized and would pass out of the still with the asphalt.

15 These limits of temperature are those which I have found to be essential with the particular oils which I have treated, but my invention is not limited to these particular temperatures as long as the temperatures 20 are maintained between the lower and upper points above indicated, as determined by the results desired.

25 The asphalt flows continuously out of the still through the pipe 24, the valve in this pipe and that in the supply pipe 2, being preferably so adjusted that this continuous flow takes place.

30 The vaporized constituents pass out through pipe 13 into the condenser and thence, as liquid, into container 23.

35 This condensate is, when the process is properly carried out, practically free from any asphaltic constituents. It has a specific gravity of about 32° Bé., as compared with the crude starting material having a gravity of from 10° to 24° Bé. In operation, no 40 deposits have been found on the bottom of the chamber 3.

45 It will be understood that this first cracking operation is carried out under substantially atmospheric pressure, the still and condenser being constructed of such proportions and arrangement that substantially no pressure is permitted to exist.

50 The condensate from container 23 may be used as the starting material for a further series of the usual refining operations to obtain gasoline, kerosene, and heavy and light lubricating oils.

55 When it is desired to further transform this first condensate into a lighter hydrocarbon of the gasoline or motor fuel type, the condensate is pumped from tank 23, by pump 26 into storage tank 27 from which it is delivered through pipe 28 into the second cracking still A', which is of the same construction as still A. The exit pipe 29 and tank 30 may be omitted, as practically no residues have occurred from the oils 60 which I have treated.

65 The vapors pass from still A' through pipe 31 into condenser B', from which the condensate is delivered through pipe 32 into tank 33.

65 In this still A', the temperature is maintained as closely as possible at 650° F., the permissible range of temperature being between about 640° F. and about 660° F. The condensate has a gravity of about 50° Bé. at 60° F.

70 Any suitable pressure may be used in this still. In practice it has been operated at substantially atmospheric pressure.

75 This condensate is then pumped by pump 34 into storage tank 35, whence it is delivered as by pipe 36 into any suitable fractionating still. I prefer to use a still A² of substantially the same construction as the stills A and A', except that the inner chamber is omitted.

80 In operation of this still, the condensate is charged into the still up to about the level indicated by the dotted line 37. The temperature is then gradually raised and the vapors generated pass over through pipe 38 into condenser B², the condensed liquids 85 being delivered through pipe 39, into one or the other of the catch-tanks 40, 41 and 42.

90 The vapors coming off up to 400° F. are condensed and collected in catch-tank 42, the product being a good quality of gasoline having a gravity of about 62° Bé.

95 The vapors driven off between 400° and 500° are condensed and collected in catch-tank 41, the product having a specific gravity of about 50° Bé. This product is preferably returned by pump 43 and pipe 44 to tank 27, for re-running in still A'. The vapors driven off above 500° F. are condensed and collected in tank 40, from which they are preferably pumped back through pump 45 and pipe 46 to tank 1 for re-running in still A. The oil collected in tank 40 has a specific gravity of about 35° Bé.

100 With the oils which I have treated, I have found that there is recovered in catch-tank 40, about 10% of the oil fractionated; in tank 41, about 20%; and in tank 42, about 70%.

105 The fractionating still is shown as provided with a draw-off pipe, but in practice there has been found to be practically no residual material. This still and the still A' are preferably heated in the manner 110 described for still A.

115 It will be apparent that while I have given specific examples of the application of my method to particular oils, and have specified certain ranges of temperatures, 120 that these specific conditions may be modified and still be within the indicated scope of my invention.

I claim:

125 The process of removing asphalt from asphalt base oils which consists in continuously delivering such oil directly on to a heated surface within an externally heated still, maintained at a temperature sufficient to volatilize substantially all the high-boil- 130 ing oils, but not high enough to vaporize

asphaltic ingredients, the residual liquid oil and vapors therefrom flowing into the open still chamber, within which the temperature is maintained between 830° and 860° F., in which such residual oil flows continuously over the heated wall of the still, whereby the vaporizable constituents are freely liberated into the still spaces, removing the asphaltic residuum from the bottom of the still, and permitting all the resulting vapors to pass out together to a condenser.

In testimony whereof, I affix my signature.

ERNEST O. LINTON.
